UNITED STATES PATENT OFFICE.

MOSES C. McMILLAN, OF WILMINGTON, OHIO.

HINGE FOR UMBRELLA-RIBS.

1,103,799.

Specification of Letters Patent. Patented July 14, 1914.

Application filed November 14, 1913. Serial No. 801,055.

To all whom it may concern:

Be it known that I, MOSES C. McMILLAN, a citizen of the United States, residing at Wilmington, in the county of Clinton and State of Ohio, have invented certain new and useful Improvements in Hinges for Umbrella-Ribs, of which the following is a specification, reference being had therein to the accompanying drawing.

10 This invention relates to hinges for umbrella ribs and is in the nature of an improvement upon the patent granted to John V. Baird March 15th, 1910, No. 951,898. This patent in common with others discloses the idea of a rib jointed between its ends so that the outer portion thereof can be folded upon the inner portion, folding the cover between them, thus reducing the length of the umbrella and enabling the same to be 15 packed in a small space, such, for example, as a hand bag. The main problem to be solved in producing a foldable rib of this kind is that of providing a hinge which will hold the ribs rigidly in their extended positions and which will permit them to be 20 quickly and easily moved into their extended positions or folded. As a general rule it is necessary either to impart some lengthwise or lateral movement to one part of the rib 25 in order to disengage the fastening device or to manipulate the fastening device itself. Such constructions are unsatisfactory for 30 two reasons. First, it makes the folding process a rather slow and tedious one and 35 destroys any popularity the umbrella might otherwise have. In the second place, the fastening devices usually present projections or parts which will pinch or catch in the cover and are liable to tear or injure the 40 same.

The object of the present invention is to provide a hinge for an umbrella rib which can be moved into either its folded or its extended position by the mere application 45 of pressure to the outer portion of the rib in the direction in which it is desired to move the same and which will be firmly held in its extended position.

Further, it is an object of the invention to 50 provide such a hinge which will have no projecting parts or catches which are likely to snag or injure the fabric of the umbrella cover; and further, to provide such a hinge which can be very easily and economically manufactured.

In the accompanying drawings, Figure 1

is a sectional view showing one of the ribs of an umbrella with my invention applied thereto; Fig. 2 is a plan view of the hinge; Fig. 3 is a transverse, sectional view, taken on the line *x* *x* of Fig. 2; and Fig. 4 is a perspective view of a hinge showing the two portions thereof partially folded.

In these drawings I have illustrated one embodiment of my invention and have shown the same as applied to an umbrella comprising a rod, to the upper portion of which the ribs are pivoted in the usual manner. I have shown but one complete rib and this is provided with my improved hinge. This rib is divided between its ends, preferably near the center thereof into two parts. That portion of the rib which is pivotally connected to the rod may be called the inner portion and is indicated by the reference numeral 1. The other portion of the rib, 2, which is pivoted to the outer end of the portion 1 of the rib, may be termed the outer portion. Both portions of the rib are provided at their adjacent ends with hinge members 3 and 4, respectively, which members are rigidly secured to the respective portions of the rib. The hinge member 3 is substantially U-shaped in cross section and is pivotally connected at a point remote from its outer end to the inner end of the hinge member 4. At the point of connection with the other hinge member the side walls of the U-shaped hinge member are substantially parallel but the forward portion of the upper edge of one of the side walls of the U-shaped member 3 is bent inward, as shown at 5, to form a lip. This lip varies in width from a point near the point of connection with the hinge member 4 to the outer end thereof so that the edge of the lip is oblique to the length of the rib. The hinge member 4 is adapted to fit into the U-shaped portion when the two portions of the rib are in their extended position and, as shown in Fig. 3, the side walls of the hinge member 4 converge downwardly so as to give the rib a tapered shape in cross section. Consequently, when the hinge member is moved about its pivot to bring it into alinement with the member 3 the inclined side wall will engage the oblique edge of the lip 5 and readily force that lip outward, so that the hinge member may pass it. As soon as the hinge member has been moved into alinement with its companion hinge member the resiliency of the metal of which the hinge is

made will cause the lip 5 to spring back into its normal position and will thus cause it to engage the top of the hinge member 4. The upper portion of the hinge member being broad and curved about a relatively long radius the contacting surface of the two hinge members will be such that considerable pressure must be applied to the outer member in order to force the lip 5 out of engagement therewith and allow the two hinge members to be folded one upon the other. Consequently, the lip serves to very firmly secure the two hinge members in their extended positions. To assist in holding the hinge member 4 against that side of the U-shaped hinge member which has the lip 5, I have provided the opposite wall of the U-shaped member with an inwardly and downwardly extending portion 6 which constitutes a resilient wall or spring bearing against the side of the hinge member 4 and tending to force the same toward the opposite side of the U-shaped hinge member. This feature is not essential to the successful operation of the device but gives an added degree of rigidity to the hinge without materially increasing the pressure necessary to fold the same.

The operation of the hinge will be readily understood from the foregoing description and it will be apparent that when the hinge is in either its extended or its folded position there are no projecting parts or catches which might interfere with the handling of the device or injure the cover. Further, it will be apparent that when the device is in its extended position the rib will be very rigid and not adapted to be moved about its hinge by any ordinary pressure applied to the umbrella; that the hinge can be folded or moved into its extended position and locked there by a direct pressure in the direction of the movement desired. Moreover, the hinge is capable of being made of two pieces of metal, as shown in the drawings, which may be folded into the desired shapes, thereby enabling the hinge to be manufactured very economically, at the same time giving an added strength thereto.

While I have shown and described one embodiment of my invention it will be understood that this has been chosen for the purpose of illustration only and that I do not desire to be limited to the details of construction shown and described, for obvious modifications will occur to a person skilled in the art.

Having thus fully described my invention, what I claim as new and desire to secure by Letters Patent, is:—

1. A hinge of the character described comprising two members, one of said members having a substantially U-shaped portion of resilient material and the other of said mem-

bers being pivotally connected at its end between the walls of said U-shaped portion of the first-mentioned hinge member at a point remote from the end of said U-shaped portion, the edge of one of the side walls of said U-shaped portion of said first-mentioned hinge member being bent toward the other wall of said hinge member to form a lip, said lip having its edge extending obliquely to the length of said hinge member and arranged to be engaged by the last-mentioned hinge member to cause said lip to move laterally to permit said last-mentioned hinge member to enter the space between the side walls of the U-shaped hinge member and to lie beneath said lip when the latter has returned to its normal position.

2. A hinge of the character described comprising two members, one of said members having a U-shaped portion and the second member being pivotally connected between the walls of said U-shaped member at a point remote from the end thereof, one of the walls of said U-shaped portion having one edge bent inward to cause it to extend obliquely to the length of said hinge member, said second hinge member having its side walls converging downwardly and having its upper edge of a width greater than its lower edge, whereby as said second hinge member is moved into alinement with said U-shaped hinge member its side wall will engage said obliquely extending lip and move the same laterally to permit said second hinge member to pass between the walls of said U-shaped hinge member and to permit said lip to engage the wide upper edge of said second hinge member.

3. A hinge of the character described comprising two members, one having a U-shaped portion and the other being pivotally connected between the walls of said U-shaped portion at a point remote from the end thereof, one of the walls of said U-shaped portion having its upper edge bent inward to cause it to extend obliquely to the length of the hinge member, whereby as the last-mentioned hinge member is moved into alinement with the first-mentioned hinge member it will engage said obliquely extending lip and move the same laterally to permit said hinge member to pass beneath said lip, that side of said U-shaped hinge member opposite the side having the lip being provided with a portion to bear against said last-mentioned hinge member and retain the same in engagement with said lip.

4. A hinge of the character described comprising two members, one having a U-shaped portion and the other being pivotally connected to said U-shaped portion and adapted to be moved into a position between the side walls thereof, one of the side walls of said U-shaped portion having a lip ar-

ranged to extend above the last-mentioned hinge member when said last-mentioned hinge member lies between the side walls of said U-shaped hinge member and the other side wall of said U-shaped hinge member having a resilient portion extending inwardly and downwardly therefrom in a position to be engaged by said last-mentioned

hinge member and serving to move the same toward that side wall which has the lip. 10

In testimony whereof, I affix my signature in presence of two witnesses.

MOSES C. McMILLAN.
